BEVERAGE BAR FIXTURE

Laurence E. Smith, Cincinnati, Ohio

Application September 8, 1948, Serial No. 48,263

3 Claims. (Cl. 312—140.4)

1

This invention relates to a tray rest which can be attached to a serving or beverage bar or the like to provide a platform for resting a tray during the filling of orders and for other purposes.

An object of this invention is to provide a stable platform on which a serving tray may be supported and which can be attached to a conventional serving bar for supporting a tray.

A further object of this invention is to provide a tray rest which can be removably attached to a bar without damaging the finish of the bar.

A further object of this invention is to provide a tray rest of the type set forth having a platform which can be pivoted or swung away from the bar to permit cleaning beneath the tray rest and to provide access to the bar and bar-fixtures beneath the same.

A further object of this invention is to provide a tray rest which can be positioned at a serving station at a bar to prevent interference by customers with servers at the serving station.

A further object of this invention is to provide a tray rest of the type referred to above which may be provided with a towel rack and other adjuncts.

The above and other objects of this invention are attained by the means described herein and illustrated in the accompanying drawings, in which:

Figure 1 is a perspective view showing a tray rest constructed in accordance with an embodiment of this invention;

Fig. 2 is a side elevational view of the tray rest; and

Fig. 3 is an exploded perspective view showing the construction of a part of the hinge connection between the platform and support sections of the tray rest.

Briefly, the present invention provides a tray rest which can be attached to a conventional type of bar having a hump along an outer edge thereof, or to other types of bars. The device includes a bracket section which can be attached about the edge of the bar. A platform section is hinged to the bracket section and may extend across the bar from the bracket section to form a platform above the bar. When desired, the platform section may be swung upwardly away from the bar to permit cleaning thereof and to permit access to fixtures of the bar located beneath the platform section. The bracket and platform sections are equipped with legs which support them in spaced relation above the bar to permit drainage thereof. Both the

2

bracket section and the platform section may be formed of strips or bars of metal or the like, appropriately joined together to form the sections. The legs which support the platform section may be rubber-tipped to prevent damage to the bar. A towel rack or other auxiliaries may be attached to the bracket section for convenience.

In the drawing a tray rest is illustrated having 10 a stationary bracket section indicated generally at 10. A hinge 11 joins a platform section indicated generally at 12 to the stationary bracket. A towel rack 13 is attached to the bracket section. The platform may be turned on the hinge to the 15 "out-of-the-way" position of Fig. 2 or to its normal supporting position of Fig. 1.

The bracket section includes a plurality of flat strips 14 curved to fit an outer edge of a bar 16 of the type common in taverns and other food-and-drink dispensing establishments. In Fig. 2 the bar is indicated in dot-dash lines. As shown, each of the strips 14 is curved to substantially a C-shape. An outer edge 17 of the bar includes an upwardly extending hump 18 and a lower ridge 19, about which each of the strips 14 can fit. Lower ends 21 of the strips are held together by a flat transverse bar or link 22, which may be riveted or otherwise firmly attached to the lower ends 21. Upper ends or portions 23 of strips 14 are bent to be horizontal when attached to the serving bar and are linked by a second transverse bar 24, to which the strips may be riveted as shown. As indicated, portions 23 are substantially horizontal when attached to the bar.

25 Two short legs 26 extend downwardly from opposite ends of transverse bar 24 and carry suction cups 27, which can rest on an upper surface 28 of bar 16 just inside the hump to support the upper end of the bracket section in spaced 30 relation above the bar. Screws 29 threaded in lower transverse bar 22 can be forced against a lower surface 31 of serving bar 16 to hold bracket section 10 in place on the bar. The screws 29 can be turned to embed conical points 32 thereof in the lower surface of the bar. However, suction cups 27 protect the upper finish of the bar and prevent marring thereof. The screws 29 and legs 26 may be directed toward each other and, as shown, may be co-planar for firmly holding the bracket section in place.

35 The platform section 12 is made up of a series of metal strips 33, which may extend away from hinge 11 substantially as extensions of strips 14. Details of construction of hinge 11 are set forth below. Outer ends 36 of strips 33 are joined

by a transverse bar or link 37, to which the strips may be riveted or otherwise firmly fixed. Legs 38 are attached to opposite ends of bar 37 to extend downwardly therefrom. Lower tips 39 of the legs 38 may be equipped with buttons of rubber or the like for resting on bar 16 or a bar fixture 41, as shown in full lines in Fig. 2. Outer ends 36 may be bent downwardly toward the bar, as shown, to be out of the way.

The construction of hinge 11 between the bracket and platform sections is most clearly shown in Fig. 3. A tip 43 of each strip 14 extends beyond transverse bar 24 and is cut away, as shown, along the center line. Each tip 43 is bent to fit about a pivot pin 44. An inner tip 46 of each strip 14 is similarly cut away along the center line and bent about pin 44. Spacers 47 fit about pin 44 to separate adjacent strips. Caps 48, a cap at either end of the pin 44, have pins 49 which fit in axial bores in pin 44 to hold hinge 11 in assembled relationship, as shown in Fig. 1. The cut-away tips 46 and 43 face each other and permit the platform section to swing about the pivot 34 to the position shown in dotted lines in Fig. 2, to provide access to the bar and to bar fixtures beneath the platform section. As shown in Fig. 3, shoulders 50 and 51 on the tips 43 and 46, respectively, are spaced a sufficient distance from pin 44 to permit the platform section to swing about the pin to the elevated position shown in dotted lines (Fig. 2) at which shoulders 50 and 51 abut the strips to hold the platform section in elevated position.

The towel rack 13 is attached to opposite outer strips 14 by brackets 52. Each of the brackets 52 has a lower curved portion 53 which fits about the towel rack 13. Upper ends 54 of the brackets 52 are bent to fit against the lower portions of the strips 14 and are firmly attached to the strips by riveting or other durable means.

The tray rest is adaptable for attaching to any conventional bar having a hump about its outer edge or may be attached to other types of bars. The strips of the platform section form extensions of the upper portions 23 of strips 14 of the bracket section, and the platform section, and portions 23 form a stable tray rest. The device is decorative yet it forms a sufficient block or obstruction to keep customers away from the server's station. The suction cups 27 and rubber tips 39 prevent damage to the upper surface of the bar. When it is necessary to clean the bar or to reach bar fixtures beneath the platform, the platform section 12 may be swung back to the position shown in dotted lines in Fig. 2 to provide ready access to the portion of the bar beneath the tray rest.

The device is preferably made of strips of sturdy, corrosion-resistant metal such as stainless steel, but may readily be constructed of other materials such as copper, aluminum, brass, or plastic materials, or the like. Many variations in the construction of the device are possible, and the invention is not intended to be limited by the foregoing detailed description and the drawing, but only as set forth in the appended claims.

What is claimed is:

1. A tray rest for a beverage bar having an exposed side edge, said tray rest comprising an elongated bracket section of substantially C-shape in section, the upper arm of said bracket section being substantially flat, means attached to said bracket section for resting on the top of the bar to support the upper arm of said bracket section

in spaced relation above the bar, clamp means attached to the lower arm of the bracket section and adapted to engage the bottom of the exposed edge of the bar to hold the bracket section on the bar with the upper arm of the bracket section substantially horizontal, a platform section having a flat upper side, a hinge connecting the platform section with the bracket section, said hinge being disposed below the upper side of the platform section, means for holding the platform section spaced above the bar the same distance as the upper arm of the bracket section, the tray rest being unobstructed above the upper arm of the bracket section and the upper side of the platform section, whereby a tray may be slid onto the platform section without obstruction, the platform section being adapted to swing upwardly on said hinge to render the top of the bar accessible.

2. In combination with an elongated beverage bar having an exposed side edge, a tray rest which comprises a bracket section including a C-shaped gridiron of closely spaced members extending around the exposed side edge of the bar, a pair of legs extending downwardly from the upper arm of the bracket section and resting on the top of the bar to hold the upper arm of the bracket section spaced above the top of the bar, a pair of clamping screws threaded in the lower arm of the clamping section and in engagement with the bottom of the exposed side edge of the bar to hold the bracket section with the upper arm thereof substantially horizontal, a platform section, said platform section including a gridiron of closely spaced coplanar members, a hinge connecting the platform section and the bracket section, said hinge being disposed therebelow, and a leg attached to the platform section remote from the hinge and adapted to rest on the top of the bar and support the platform section in horizontal alignment with the upper arm of the bracket section, the platform section and the upper arm of the bracket section being unobstructed above their upper faces, whereby the platform section forms a continuation of the upper arm of the bracket section and a tray may slide onto the top of the platform section from the exposed side edge of the bar without obstruction, the platform section being adapted to swing upwardly on said hinge away from the bar to expose the top of the bar.

3. A tray rest for an elongated beverage bar having an exposed side edge, said tray rest comprising a bracket section including a plurality of C-shaped bars, a pair of spaced connecting bars attached to and extending between the C-shaped bars to maintain the C-shaped bars in spaced parallelism to form the bracket section, upper arms of the C-shaped bars being straight and coplanar, the bracket section being adapted to extend around the exposed side edge of the beverage bar with the upper arms of the C-shaped bars horizontal and spaced above the top of the bar, a pair of downwardly extending legs attached to the upper arms of the C-shaped bars and adapted to rest on the top of the beverage bar to maintain the upper arms spaced above the beverage bar, and a pair of clamping screws threaded in the lower arm of the bracket section and adapted to engage the bottom of the outwardly extending edge to hold the bracket section on the beverage bar, and a platform section, said platform section including a plurality of closely spaced bars adapted to extend transversely of the beverage bar, a pair of connecting bars attached

to and extending between the transverse bars to hold the transverse bars in closely spaced parallelism, a hinge connecting the platform portion to the upper arms of the bracket section, said hinge being disposed therebelow, and a leg attached to the platform section remote from the hinge and adapted to rest on the top of the beverage bar and support the platform section in horizontal position with the upper sides of the transverse bars in alignment with the upper sides of the upper arms of the C-shaped members, the tray rest being unobstructed above the upper arms of the C-shaped members and the upper side of the platform section, whereby a tray may be slid onto the platform section without obstruction, the platform section being adapted to swing upwardly on said hinge for rendering the top of the beverage bar accessible.
